GRAINING-TOOL.

No. 839,364.

Specification of Letters Patent.

Patented Dec. 25, 1906.

Application filed May 21, 1906. Serial No. 317,893.

To all whom it may concern:

Be it known that we, WALTER L. COOKE and ALBERT H. BATES, citizens of the United States, residing at Cleveland, in the county of Cuyahoga and State of Ohio, have invented a certain new and useful Improvement in Graining-Tools, of which the following is a full, clear, and exact description, reference being had to the accompanying drawings.

The object of this invention is to provide a simple and efficient graining-tool adapted for use in giving the effect of the natural grain to the wood—as floors, for example. A rubber structure having concentric grooves has heretofore been employed for this purpose, either in flat form or tubular form. These devices are lacking in that they do not have a handle for the convenient manipulation of the graining-tool, while the tubular tools have the further disadvantage that their cylindrical surface cannot be brought into engagement with the floor immediately adjacent to the wall, wherefore that portion of the floor is very liable to present a different appearance from the rest.

Our invention is designed to overcome this difficulty and provide a graining-tool having a handle for ordinary manipulation, the graining-pad being held on a cylindrical head, while for starting the operation at the walls and other places the tool may be used flat.

This invention makes the tool universal in its application and at the same time very convenient in its operation.

The drawings clearly disclose the invention.

Figure 1 is a perspective view of the tool complete with the graining-pad in the position it usually occupies. Fig. 2 is a cross-section through the head on a plane out of the diameter, as indicated by the line 2-2 of Fig. 3. Fig. 3 is a side elevation of the tool with the graining-pad free for use as a flat surface adjacent to walls or as a concave surface on columns, &c. Fig. 4 is a bottom view of the graining-pad itself.

Referring to the parts by letters, A represents the cylindrical head, which may be of wood, and B the handle, which may be secured to the head by extending into a hole

therein. Secured to a portion of this head is a soft backing C, of felt or similar material, and outside of this is the graining-pad D. This pad is preferably of rubber and has on its under face concentric grooves d, as shown. The grooves are preferably not completely circular, but semicircular, except those which are of such size as to be intercepted by the edges of the pad. The pad is secured to the head along that edge of the pad which is substantially in the line of the diameter of the grooves—that is, the bottom edge in Fig. 3.

In the drawings, F indicates tacks which secure both the pad and one edge of the backing-sheet to the head. The other edge of the backing member is secured to the head in a suitable manner, as by tacks. (Not shown.)

To conveniently hold the pad in curved form about the head, we provide a bale E, which has ends turned into openings in the ends of the head and has an intermediate portion e, adapted to extend across the pad D and hold it in place, as shown in Fig. 1. The inturned ends of the bale take into openings in the head at the points indicated by a, which are between the axis of the head and the side thereof where the pad rests, being nearer the secured end of the pad than the free end. This eccentric pivoting causes the bale to pinch the pad more tightly the more it is forced onto the pad, thus enabling it to securely hold the pad in curved position, (shown in Fig. 1,) while when the bale is swung in the opposite direction it immediately clears the pad, releasing it.

The path of movement of the clamping portion e of the bale is indicated by the broken line in Fig. 3. In the released portion if the bale is swung upward substantially against the under side of the handle it bears against the head with friction sufficient to hold it in this position against accidental displacement.

It will be seen that our tool normally provides a cylindrical surface with a handle, which is the most convenient form for the usual graining. The soft backing member allows the tool to be used in this form on surfaces possessing considerable unevenness—as warped boards, for example—while by simply

swinging the bale the pad becomes flat and may be used wherever a flat surface is desirable.

Having thus described our invention, we claim—

- 5 1. In a graining-tool, the combination of a body and a graining-pad permanently secured thereto at one edge and free at the other.
- 10 2. In a graining-tool, the combination of a solid wood head having a curved under portion, a flexible curved pad secured at one edge to such head and adapted to be used flat or curved about the head.
- 15 3. In a graining-tool, the combination of a cylindrical wooden head, a flexible grooved pad secured at one edge to such head and a soft backing member between the pad and head.
- 20 4. In a graining-tool, the combination of a head, a flexible pad secured at one edge to such head, and a bale secured to the ends of the head and adapted to extend across the pad.
- 25 5. In a graining-tool, the combination of a cylindrical head having a handle, a flexible pad secured at one edge to such head and adapted to be used flat or curved about the head, and a bale secured to the ends of the
- 30 head adapted to extend across the pad, the bale being pivoted eccentrically, so as to bind the pad in clamping it and free the pad in releasing it.
6. In a graining-tool, the combination of a

rigid cylindrical head, a grooved pad adapted to lie about a portion of the cylindrical surface, said pad having less areal length than the circumference of the cylinder, means for holding the pad permanently at one edge and freely at the other, and a handle secured to the head on the opposite side from the pad.

7. In a graining-tool, the combination of a solid wooden cylindrical head, a handle set into a central radial opening in the head, a grooved pad adapted to lie about that portion of the head which is substantially opposite the handle, the edges of said pad being a considerable distance from said handle, means for permanently holding one edge of the pad to the head, and means for temporarily holding the other edge of the pad to the head.

8. In a graining-tool, the combination of a head having a curved under portion, a flexible pad secured at one edge to such head and adapted to be used flat or curved about the head, and a soft backing between the pad and head, said backing being secured at both edges to the head.

In testimony whereof we hereunto affix our signatures in the presence of two witnesses.

WALTER L. COOKE.
ALBERT H. BATES.
